AIR CONTROL RECEIVER

James D. S. Drinkwater, Chester, England, and
 John H. D. Petersen, Chicago, Ill., assignors to
 Link-Belt Company, a corporation of Illinois

Application November 2, 1932, Serial No. 640,862

7 Claims. (Cl. 209—500)

Our invention relates to improvements in pneumatic drive mechanisms and processes of operating wash boxes or jigs of the Baums or air actuated type and is especially applicable to a wash box or jig where water is circulated through a flowing sheet of material to be concentrated or gravitally separated by means of the intermittent application of pneumatic pressure to a closed portion of the wash box whereby the water therein is by pneumatic pressure forced upwardly through the bed of material to be separated.

Experience shows that under some circumstances, it is desirable to modify or vary the velocity of the water as it passes upwardly through the bed of material during different parts of the same stroke or impulse especially if we are separating materials whose specific gravities are not widely different. Experience has taught us that if we start each impulse suddenly and violently and decrease the force of the impulse toward the end thereof, greatly improved separation takes place. We accomplish this by providing any suitable means for compressing air or gas and supplying it to the wash box, there being between the compressor and the wash box, a mechanically operated valve which opens and closes. When it opens, it admits air under pressure to the closed chamber thereby applying pressure to the water. When it is closed, it shuts off the air and permits the air already trapped in the chamber to escape. This opening and closing of the valve of course sets up a pulsating action in the water and it is this that provides the pulsating stream of water upwardly through the bed of material to be separated.

Normally the air control or quick opening valve when open, admits during the entire open period a continuous flow of air at uniform pressure, because the air is supplied to the header at a rate sufficient to cause the operation of the machine and sufficient to accomplish this. Thus the speed of flow of the water through the bed of material is under these circumstances substantially the same during the entire upward flow period.

Experience shows that an important factor in the operation of the machine of the kind with which we are dealing is the rate of speed at which water is forced upwardly through the bed of material to be classified or concentrated. It is obvious that the speed at which this water is forced through the bed depends upon the pressure of the air in the air pocket associated with the water. We propose to control the operation of the bed by controlling the pressure of

the air in the pocket where it produces its effect on the water. Preferably we find that it is desirable to start the upward movement of the water through the bed at a maximum and gradually decrease the velocity of the water. This can be done by exerting a maximum pressure in the air pocket at the beginning of the upward movement of the water and allowing or causing this pressure to gradually decrease down to any desired minimum.

We have found in actual practice that without any other change in the jig, the capacity can be increased as much as thirty or thirty-five percent by controlling the rate of flow of the water upwardly through the bed as above indicated and this increase in capacity is accompanied by an improved effectiveness of separation.

This control of the air pressure and so control of the bed may obviously be accomplished in many different ways. Our preferred means takes the form of a separate air receiver associated with each cell of the wash box, together with means for supplying air to each cell and valves for controlling the volume of such air as it is supplied to and discharged from the receiver to the air pocket. This control is accomplished by the use of manually adjusted valves between the receiver and the quick acting valve and between the receiver and the air supply for controlling the flow of air to the receiver and the flow of air from the receiver to the quick acting valve.

Assuming a continuous supply of air under uniform pressure, when the quick acting valve is closed, pressure will be built up in the receiver to substantially the pressure of the uniform air supply. When the quick acting valve is opened, the air under pressure in the receiver will rush out through the quick acting valve into the air pocket creating a maximum air pressure in the air pocket and so exerting a maximum displacing effect on the water. As the pressure in the receiver falls, the pressure applied to the water will also fall, the throttling of the air supply to the receiver making it impossible for the air supply to maintain the pressure in the receiver and so in the air pocket at a maximum. This pressure as it falls permits the rate of speed of water flowing through the bed to decrease down to a minimum which may be selected by the operator who adjusts the throttling valve between the air supply and the receiver to accomplish his desired adjustment.

The rate at which the air will be discharged from the receiver and the relation between the

contribution made by the receiver and the uniform air supply to the air pocket is controlled by manipulation of the throttle valve between the receiver and the quick acting valve and the 5 throttle valve between the receiver and the main air supply so that the operator can control the action of his bed within a wide range of variations from an adjustment where the water rushes through the bed at maximum speed throughout 10 the entire open period of the quick acting valve to an adjustment where the water velocity falls almost to zero toward the end of the open period of the quick acting valve.

Our invention is illustrated more or less dia- 15 grammatically in the accompanying drawings, wherein—

Figure 1 is a top view;

Figure 2 is a front elevation;

Figure 3 is a section along the line 3—3 of 20 Figure 2;

Figure 4 is a detail side elevation in part sec- 25 tion showing the air control apparatus.

Like parts are indicated by like characters 30 throughout the specification and drawings.

25 A is a wash or jig box having a curved bottom A¹ and supported on a framework A². It is divided into two longitudinal sections by a longitudinal partition A³ which extends down into the body of the box below the surface of the water 35 maintained therein and divides the box longitudinally into air and working areas. The box is also divided up into a series of separate compartments A⁴ A⁴ and A⁵ A⁵ by transverse partition walls A⁶, A⁷, which extend upwardly on the air side of 40 the box as far as the heads A⁸ which close each of the air compartments and on the jiggling side extend up to the screens A⁹ A¹⁰ which are set at different levels, the screen A⁹ which is at slightly higher level than the screen A¹⁰ being on the upstream end of the box. Raw material, for instance coal, is fed into the box through the sluice A¹¹ and treated coal is discharged in a concentrated condition through the sluice A¹².

45 B is a screw conveyor located in a trough at the bottom of the wash or jig box A and is adapted to discharge refuse material, which passes through the screens and drops down into the body of the water, into the refuse elevator boots B¹ B² located at either end of the box. B³ B⁴ 50 are refuse gates at the intake and discharge ends of the screen, adapted to be controlled by hand wheels B⁷ B⁸ at the front of the machine. Refuse gravitates to the bottom of the bed of flowing coal upon the screen and particles too large to 55 pass through the screen pass out between these gates and the screen through the chutes B⁵ B⁶ and are discharged thereby into the refuse elevator boots. When coal is being treated, this refuse is dirt, clay, slate, shale, bone coal, and the like, 60 which is heavier than the coal from which it is separated by gravity. It will be understood that the water level in the jig box is maintained high enough above the screens so that the entire bed of material as it travels along them is submerged.

65 Associated with each one of the air pockets is a quick acting valve C, comprising a reciprocating piston member driven by a stem C¹, and connecting rod C² from an eccentric C³ on the valve operating shaft C⁴. Air is supplied to each of these 70 valves from a header C⁵ through a pipe C⁶ controlled by a manually adjusted valve C⁷, a receiver C⁸ and a manually adjusted valve C⁹, there being one quick acting valve and two manually 75 adjusted valves and one receiver for each air

pocket. The quick acting valve as it reciprocates, alternately causes compressed air to be supplied to the air pocket and to be discharged therefrom to the atmosphere. When air passes in through the valve C from the receiver C⁸ to the air pocket, 5 it forces the water down on the air side of the longitudinal dividing walls A³ and this water rushes up through the screen and through the bed of material on the screen tending to raise and suspend the material and since the velocity 10 of the water starting at a maximum gradually decreases, the heavier particles tend to descend under the influence of gravity more rapidly than the lighter particles. This progression is gradual in response to change in water velocity so that 15 stratification is thereby made more positive, more rapid and more effective. When the quick acting valve C permits air to escape from the pocket, the water tends to return by gravity in a reversed direction through the bed of material and 20 the screen. At the same time the materials which remain in suspension at the end of the upward excursion of the water responsive to the opening of the quick acting valve settle back on the screen at a rate of speed more or less proportion- 25 ate to the specific gravity of the individual particle. This cycle of operation results in accurate, rapid and controlled stratification of the material leaving the heavy material nearest to the screen and the lighter materials progressively arranged above the heavier particles. Water may be supplied through the pipe C¹⁰ controlled by the manually adjusted valve C¹¹ partially to reverse velocity of the water but primarily to provide a sufficient carrying body of water to move 30 the stratified particles toward the exit end of the wash box in order that the lighter and heavier particles may be separated and separately discharged. The rate at which the valve shaft rotates controls the rate of pulsation of the water 35 in the jig box and since as will hereinafter appear the air controlled by the quick acting valve comes to it at a generally constant pressure without pulsation, the only element controlling pulsation is the quick acting valve. 40

The valve C⁷ between the header and the receiver will normally be set such that the flow of air from the header to the receiver is less than the flow of air through the valve C and when the valve C is closed, air under pressure will flow 45 from the header into the receiver until the pressure in both is equalized. When the valve C is open the expansion of the air under pressure in the receiver will together with and supplemented by the flow of air from the header to the receiver 50 give a maximum air flow and air pressure at the beginning of the stroke. As the air in the receiver expands the volume of air available will decrease to a point ordinarily such that toward the end of the stroke the air will have expanded 55 to a maximum in the receiver and the only air flowing through the valve C will be the controlled air supply forced in from the main header or compressor. At that time the valve C will close and pressure will again be slowly built up in the 60 receiver. By this arrangement the stored air in the receiver assists the compressor in furnishing air to operate the jig and because the stored air effect decreases gradually during each stroke, the velocity of the water forced upwardly through 65 the separating bed will start at a maximum and go down to a minimum toward the end of the stroke. The result of this is that as the velocity of the water decreases, particles of lighter and closer specific gravities may be given the oppor- 70 75

tunity to settle out because experience shows that these will not settle in a rapidly moving upward current of water. The violent movement at the start is necessary to start the movement upward of the particles to be separated but decreasing the velocity of the water toward the end of the pulsation stroke gives the particles an opportunity to settle in the still upward moving water at rates more or less in proportion to their specific gravity.

10 The manual control valve C⁹ is inserted in the system to make it possible to control the effect of the receiver and prevent too great run off of the air under pressure from the receiver if that is desired.

15 D is a centrifugal blower driven by a motor D¹ and discharging directly into the header C⁵. This blower furnishes air under pressure to the header at approximately constant pressure independent of volume displaced up to the maximum capacity of the blower and since the blower installed in the device is of course of big enough capacity to carry the maximum load which may be imposed upon it, it is a fact that in the main, pressure variations are reduced to a minimum so far as the 20 blower itself is concerned. The blower D draws in air through the intake pipe D¹⁰. This pipe is controlled by a blast gate D², preferably of the butterfly type. This gate is controlled by an operating rod D³ extending across the machine to 25 the front where it is provided with a handle or lever D⁴ whereby the operator may adjust it.

Since a centrifugal compressor giving generally constant air pressure independent of variations in the amount of displaced air used, and 30 since this centrifugal compressor discharges air in a constant non-pulsating flow, no large receiver is needed as would be the case if a blower giving pulsating air current were used and so the quick acting valves are the only elements in the system 35 controlling the rate of pulsation and since they release successive impulses of air at substantially constant pressure the rate of pulsation and its magnitude may be accurately controlled.

The hand control valves between the header 40 and each air pocket will be adjusted by the operator when the machine first starts to control the flow of air from the header to the quick acting valve because experience shows that usually different quantities of air should be fed to the different air pockets.

45 The blast gate in the intake to the compressor has a two-fold function. It is used to altogether stop the supply of compressed air to the system when the operator desires so to do and it is used to control the pressure of air fed to the system 50 while in operation.

It will be understood that in a sense the storage of air under full pressure in the receiver whereby the stored air in part at least accomplishes the pulsating effect is similar to the cut off in a steam engine, that is to say,—the air is stored at maximum pressure in the receiver so that as work takes place the pressure gradually falls off, thereby controlling the operation. A 55 more or less expansion effect is provided by the receiver because the supply of air to it is restricted to greater or lesser extent.

We claim:

1. In combination in a wash box, a generally longitudinal partition therein and a generally transverse partition, said latter partition dividing the box into a plurality of cells, a screen lying on one side of the longitudinal partition and a plurality of closed air pockets formed on the other side of the partition, the under side of said air

5 pockets being bounded by the surface of the water on the side of the longitudinal partition opposite the screen, means for supplying water to said wash box and for maintaining the level of said water above said screen, means for maintaining a continuously flowing bed of fragmentary material on the screen and beneath the water level, an air compressor, a general header connected to said compressor and adapted to supply air to each of said cells, there being pipes connecting said header with each of said cells, a quick acting valve associated with each of said pipes and adapted alternately to permit the inflow of compressed air from the header to each cell, and individual receivers, one for each cell, interposed between said general header and one of said quick acting valves.

2. In combination in a wash box, a generally longitudinal partition therein and a generally transverse partition, said latter partition dividing the box into a plurality of cells, a screen lying on one side of the longitudinal partition and a plurality of closed air pockets formed on the other side of the partition, the under side of said air pockets being bounded by the surface of the water on the side of the longitudinal partition opposite the screen, means for supplying water to said wash box and for maintaining the level of said water above said screen, means for maintaining a continuously flowing bed of fragmentary material on the screen and beneath the water level, an air 20 compressor, a general header connected to said compressor and adapted to supply air to each of said cells, there being pipes connecting said header with each of said cells, a quick acting valve associated with each of said pipes and adapted alternately to permit the inflow of compressed air from the header to each cell, and individual receivers, one for each cell, interposed between said general header and one of said quick acting valves, the rate of air flow from the general 25 header to each individual receiver during any selected time interval being less than the rate of flow through the quick acting valve from the individual receiver to the pocket during an equivalent time interval.

3. In combination in a wash box, a generally longitudinal partition therein and a generally transverse partition, said latter partition dividing the box into a plurality of cells, a screen lying on one side of the longitudinal partition and a plurality of closed air pockets formed on the other side of the partition, the under side of said air pockets being bounded by the surface of the water on the side of the longitudinal partition opposite the screen, means for supplying water to said wash box and for maintaining the level of said water above said screen, means for maintaining a continuously flowing bed of fragmentary material on the screen and beneath the water level, an air compressor, a general header connected to said compressor and adapted to supply air to each of said cells, there being pipes connecting said header with each of said cells, a quick acting valve associated with each of said pipes and adapted alternately to permit the inflow of compressed air from the header to each cell, and individual receivers, one for each cell, interposed between said general header and one of said quick acting valves, and manually controlled valves interposed, one between said general header and each of said individual receivers, whereby throttling may be carried out between said general header and each of said receivers.

4. In combination in a wash box, a generally longitudinal partition therein and a generally

transverse partition, said latter partition dividing the box into a plurality of cells, a screen lying on one side of the longitudinal partition and a plurality of closed air pockets formed on the other side of the partition, the under side of said air pockets being bounded by the surface of the water on the side of the longitudinal partition opposite the screen, means for supplying water to said wash box and for maintaining the level of said water above said screen, means for maintaining a continuously flowing bed of fragmentary material on the screen and beneath the water level, an air compressor, a general header connected to said compressor and adapted to supply air to each of said cells, there being pipes connecting said header with each of said cells, a quick acting valve associated with each of said pipes and adapted alternately to permit the inflow of compressed air from the header to each cell, and individual receivers, one for each cell, interposed between said general header and one of said quick acting valves, and a manually controlled valve between each of said individual receivers and the cell with which it is connected.

5. In combination in a wash box, a generally longitudinal partition therein and a generally transverse partition, said latter partition dividing the box into a plurality of cells, a screen lying on one side of the longitudinal partition and a plurality of closed air pockets formed on the other side of the partition, the under side of said air pockets being bounded by the surface of the water on the side of the longitudinal partition opposite the screen, means for supplying water to said wash box and for maintaining the level of said water above said screen, means for maintaining a continuously flowing bed of fragmentary material on the screen and beneath the water level, an air compressor, a general header connected to said compressor and adapted to supply air to each of said cells, there being pipes connecting said header with each of said cells, a quick acting valve associated with each of said pipes and adapted alternately to permit the inflow of compressed air from the header to each cell, and individual receivers, one for each cell, interposed between

between said general header and one of said quick acting valves, and manually controlled valves, one on each side of each of said individual receivers.

6. A wash box comprising a tank containing water, a longitudinal partition therein, a screen located beneath the surface of the water on one side of the partition, a closed air pocket, the underside of which is bounded by the surface of the water on the opposed side of the partition, 10 means for maintaining a continuous flowing bed of fragmentary material on the screen beneath the water level, an air receiver of less capacity than that needed for each stroke connected to the air pocket and supplying air thereto, means in 15 constant communication with the receiver for continuously supplying air to the receiver at a rate less than the rate of flow from the receiver into the air pocket, and a quick acting valve in the connection between the receiver and air 20 pocket adapted to alternately permit the flow of air from the receiver into the pocket and outflow of air from the pocket to atmosphere, whereby operation of the quick acting valve causes movement of the water initially at high velocity and 25 then at gradually decreasing velocity after the air in the receiver has been exhausted.

7. The method of gravitally separating a mass of fragmentary material which consists in supporting the mass in a body of fluid, continuously 30 supplying air at a uniform rate to a storage compression zone, discharging air from said zone into contact with the body of fluid at a greater rate than the air is supplied to said zone to cause the fluid to pass through the mass of fragmentary 35 material at high velocity, separating the lighter particles from the mass, and continuing the supply of air to the storage zone and through the zone into contact with the body of fluid after discharge of the stored air from the storage zone, 40 whereby the body of fluid is moved initially at high velocity and subsequently at gradually decreasing velocity.
